UNITED STATES PATENT OFFICE.

ISAAC A. HORTMAN, OF PHILADELPHIA, PENNSYLVANIA.

PROPELLER.

979,672.

Specification of Letters Patent. Patented Dec. 27, 1910.

Application filed February 11, 1909. Serial No. 477,368.

To all whom it may concern:

Be it known that I, ISAAC A. HORTMAN, a citizen of the United States, residing at Philadelphia, in the county of Philadelphia and State of Pennsylvania, have invented 5 certain new and useful Improvements in Propellers, of which the following is a specification.

This invention relates to marine propul- 10 sion and more particularly to a reversible propeller for steam ships and other marine vessels.

The object of the invention is to provide 15 a propeller by means of which the direction of travel of a vessel may be reversed without the necessity of reversing the engine or other motive power.

A further object is to provide a propeller, 20 the blades of which are mounted for oscillation on the driving shaft and operatively connected to an actuating member so that when the latter is operated the blades will be given a quarter turn and thus reverse 25 the angle or inclination of said blades with respect to the driving shaft.

A further object is to provide means for 30 changing the angle or inclinations of the blades with respect to the driving shaft and means for locking said blades in adjusted position.

A still further object of the invention is 35 generally to improve this class of propellers so as to increase in utility, durability, and efficiency.

Further objects and advantages will appear 40 in the following description, it being understood that various changes in form, proportions, and minor details of construction may be resorted to within the scope of the appended claims.

For a full understanding of the invention and the merits thereof and also to acquire a knowledge of the details of construction and the means for effecting the result, reference is to be had to the following description and accompanying drawings, in which:

Figure 1 is a longitudinal sectional view 45 of the reversible propeller constructed in accordance with my invention; Fig. 2 is a transverse sectional view taken on the line 2—2 of Fig. 1; Fig. 3 is a similar view 50 taken on the line 3—3 of Fig. 1; Fig. 4 is a detail perspective view partly in section, showing one of the propeller blades in re- 55 versed position; Fig. 5 is a similar view

showing the propeller blade in normal position; Fig. 6 is a transverse sectional view of one of the propeller spindles showing the manner of locking the same against oscillation in one direction; Fig. 7 is a similar 60 view showing the spindle locked against oscillation in the other direction; Fig. 8 is a perspective view of one of the propeller blades detached showing the manner of connecting the actuating rod therewith and 65 also showing the position of the locking pawl relative thereto; Fig. 9 is a perspective view of one of the propeller blades showing the locking pawl disengaged from the shoulder in the adjacent actuating rod; Fig. 10 70 is a detail perspective view of the lower portion of one of the propeller blades; Fig. 11 is a perspective view of the casing detached.

Corresponding and like parts are referred to in the following description and indicated 75 in all the views of the drawings by the same reference characters.

The mechanism forming the subject matter of the present invention is principally designed for propelling steam ships and 80 other marine vessels and by way of illustration is shown in connection with a steam ship of the ordinary construction, in which 5 designates the hull of the vessel, and 6 the driving shaft. The driving shaft is pro- 85 jected longitudinally beyond the stern of the hull, and keyed or otherwise rigidly secured to the projected end of the shaft, is a casing 7 having a plurality of radiating arms 8, preferably four in number as shown, and 90 each provided with a transverse bore 9 constituting a bearing for the propeller blades 10. The blades 10 are mounted for oscillation 100 in the radiating arms 8 and are each provided with a reduced shank or spindle 11 95 which engages the bearing of the adjacent arm, there being spaced locking lugs 12 and 13 extending laterally from the spindle end of each blade for the purpose hereinafter referred to. Each radiating arm 8 is pro- 100 vided with a removable face plate 14 having a vertical groove formed therein, which groove in connection with the bore 9 constitutes the bearing for the spindle. The inner end of each blade spindle is formed 105 with an enlargement or shoulder 15 to which is secured in any suitable manner a laterally projecting arm 16 having an eye formed in the free end thereof for registration with a corresponding eye formed in an actuating 110

rod or member 17, the rods 17 being pivotally connected with the arms 16 by a bolt or similar fastening device, indicated at 18.

Keyed to the driving shaft 6 is a longitudinally movable actuating sleeve 19 having its outer end closed by a head 20 and its inner end provided with a partition or diaphragm 21, which latter is spaced from the adjacent end of the sleeve and is formed with an annular guiding groove 22. Extending longitudinally from the head 20 are locking members or rods 23, the free ends of which are bent to form angularly disposed arms 24 which enter elongated slots 25 formed in the arms of the casing 7 for connection with sliding members or blocks 26. The inner end of each locking block 26 is cut-away to produce a lip 27 arranged to engage the lug 13 of the adjacent blade and lock the latter against accidental oscillation when the blades are in reversed position.

As a means for locking the blades in a normal position, there are provided a plurality of longitudinally movable rods 28, one end of each of which is bolted or otherwise rigidly secured to the head 20, while the opposite ends thereof are slidably mounted in cylindrical bores 29 formed in the adjacent radiating arms 8 of the casing and in communication with the bearings 9 of said arms. The outer or free end of each locking rod 28 is reduced to form a terminal lip 30 arranged to engage the locking lug 12 on the adjacent spindle 11, this result being accomplished when the sleeve 19 is adjusted longitudinally of the driving shaft in the direction of the propeller blades to drive the vessel ahead. Arranged within the hull of the vessel is a transverse beam 31 having an opening formed therein for the reception of the driving shaft 6, and disposed on opposite sides of the shaft receiving opening are relatively small openings 32 which receive longitudinally movable rods 33. The inner ends of the rods 33 extend within the sleeve 19, and journaled on said rods are rollers 34 which bear against walls of the guiding groove 22 and thus prevent friction between the parts when the driving shaft together with the actuating sleeve, is rotated. The inner ends of the rods 33 may be connected to a hand operated lever, or said rods may be connected through the medium of a chain, gearing or the like, with a motor for actuating the sleeve to effect the reversal of the propeller blades. The inner end of each actuating rod 17 is slidably mounted in the head 20 of the sleeve and is provided with an offset portion or shoulder 35 defining a recess 36 adapted to receive a locking pawl or member 37, which latter serves to space the shoulder 35 from the head when the blades are in reversed position and thus cause the rod 17 to move with the head 20 of the actuating sleeve when the

latter is operated to return the blades to normal position.

Keyed or otherwise permanently secured to the operating shaft or casing 7, are a plurality of longitudinally disposed ribs 38 having inclined or cam faces, the function of which is to engage and elevate the pawls 37 from the recesses 36 in the actuating rods when the sliding sleeve 19 nears the limit of its rearward movement, so that a further longitudinal movement imparted to the sleeve will cause the locking rods 28 to engage the lugs 12 without effecting the movement of the actuating rods and consequently without rotating the blades. Arranged between the ribs 38 are smaller ribs 39 also provided with inclined cam faces which enter grooves in the pivoted ends of the locking pawls and serve to positively force the active ends of the pawls downwardly within the recesses 36 of the actuating rods 17 when the sleeve 19 has reached the limit of its forward movement and the propeller blades are in the reverse position shown in Fig. 4 of the drawings.

Suitable openings or recesses 40 are formed in the radiating arms of the casing 7 so as to permit free movement of the locking lugs 12 and 13 when the propeller blades are oscillated to effect the reversal of the vessel. Thus it will be seen that when the propeller blades are in the position shown in Fig. 5 of the drawings, the locking lips 30 of the locking rods 28 will engage the lugs 12, of the propeller blades and lock said blades in normal position so as to propel the vessel in a forward direction. In order to effect the reversal of the propeller blades it is merely necessary to operate the rods 33 which moves the sleeve 19 forwardly, and in so doing, releases the locking lips 30 from the lugs 12 and at the same time causes the actuating rods 17 to move the blades a quarter turn, so as to reverse the direction of travel of the vessel. On the initial forward movement of the actuating sleeve, the inclined faces of the ribs 39 will bear against the pivoted ends of the pawls 37 and at the completion of the forward movement of the actuating sleeve the ribs will force the active ends of the said pawls within the recesses 36, the head 20 at the same time exerting a longitudinal pull on the rods 23 and causing the lips 27 to engage the lugs 13 and lock the propeller blades in reversed position. On the initial rearward movement of the actuating sleeve, the inclined faces of the ribs 38 will bear against the active or free ends of the pawls 37, and at a point near the completion of the rearward movement of the actuating sleeve, the ribs will entirely disengage the pawls from the recesses 36 so that a further rearward movement imparted to the sleeve will cause the head to move the distance of the width of the pawls and there-

by force the lips 30 of the locking rods 28 into engagement with the lugs 12, so as to lock the propeller blades in normal position. Attention is here called to the fact that after 5 the propeller blades have been moved to normal position and the pawls disengaged from the recesses, the actuating rods 17 remain relatively stationary while the locking rods 28 are moved in opposite directions 10 into engagement with the lugs 12 thus assuring positive engagement of the lips 30 with the lugs 12 when the sleeve is adjusted for the purpose of driving the vessel ahead. Thus it will be seen that means is provided 15 for effecting the reversal of the propeller blades and means for positively locking the blades in normal and reversed positions.

A casing or housing 41 preferably surrounds the radiating arms and actuating 20 mechanism thereby to protect the same from the deleterious action of the water.

Having thus described the invention, what is claimed as new is:

1. In marine propulsion, a driving shaft, 25 a plurality of oscillating propeller blades carried by the shaft, means for changing the angle of the blades with respect to said shaft, and locking members independent of the driving shaft and actuated by the blade 30 adjusting means for securing said blades in different positions.

2. In marine propulsion, a driving shaft, a casing carried by the shaft and provided with radiating arms, propeller blades 35 mounted for oscillation in said arms, means for oscillating the blades to effect the reversal thereof, and means carried by the blade adjusting means and independent of the driving shaft for locking the blades in 40 reversed position.

3. In marine propulsion, a driving shaft, a casing carried by the shaft, a plurality of propeller blades mounted for oscillation in said casing, an actuating sleeve slidably 45 mounted on the driving shaft, rods forming connections between the propeller blades and actuating sleeve for changing the angle of the blades with respect to the driving shaft when said sleeve is operated, and 50 means actuated by the sleeve and independent of the driving shaft for locking the blades in different positions of angular adjustment.

4. In marine propulsion, a driving shaft 55 held against movement in a longitudinal plane, but free to rotate, a casing carried by the shaft, propeller blades mounted for oscillation in the casing and provided with laterally extending lugs, means slidably 60 mounted on the driving shaft for oscillating the propeller blades to change the angle of said blades with respect to the driving shaft, and longitudinally movable locking members co-acting with the lugs on the propeller 65 blades and actuated by the propeller oscil-

lating means for locking the blades in different positions of angular adjustment.

5. In marine propulsion, a driving shaft, a casing carried by the shaft, a plurality of propeller blades mounted for oscillation 70 in the casing, arms extending laterally from the propeller blades, an actuating sleeve carried by and adjustable longitudinally of the driving shaft, rods forming a connection between the actuating sleeve and arms of the 75 propeller blades, and oppositely disposed locking members movable with the sleeve and arranged to engage the propeller blades for locking the latter in normal and reversed positions.

6. In marine propulsion, a driving shaft, a casing carried by the shaft, a plurality of propeller blades mounted for oscillation in the casing, an actuating sleeve carried by and adjustable longitudinally of the driving 85 shaft, and provided with an interior groove, a connection between the actuating sleeve and propeller blades, rods having terminal rollers engaging the guiding groove for actuating the sleeve to effect the reversal of 90 the propeller blades, and means for locking the said propeller blades in normal and reversed positions.

7. In marine propulsion, a driving shaft, a casing carried by the driving shaft, a sleeve 95 mounted for longitudinal movement on said driving shaft, propeller blades arranged to oscillate in the casing, actuating rods each having one end thereof pivotally connected to an adjacent propeller blade and its opposite end slidably mounted in the sleeve and provided with a shoulder, means for adjusting the actuating sleeve to effect the reversal of the propeller blades, means for locking the propeller blades in normal and reversed 100 positions, and pawls pivotally mounted on the sleeve and adapted to bear against the shoulders when the blades are reversed.

8. In marine propulsion, a driving shaft, a casing carried by the driving shaft, a plurality of propeller blades mounted for oscillation in the casing, an actuating sleeve, rods operatively connected to the propeller blades and having their inner ends slidably mounted in the sleeve and provided with shoulders 110 defining recesses, pawls carried by the sleeve and arranged to enter the recesses when the propeller blades are in reversed position, means for locking the blades in the reversed position, and means for disengaging the 115 pawls from the shoulders when the sleeve is actuated to return the blade to normal position.

9. In marine propulsion, a driving shaft held against movement in a longitudinal 125 plane, but free to rotate, a casing carried by the shaft and provided with a plurality of radiating arms having bearings formed therein, propeller blades journaled in said bearings and provided with laterally ex- 130

4

tending lugs, an actuating sleeve slidably mounted on the driving shaft, a connection between the sleeve and propeller blades for effecting the reversal of the latter, and means actuated by said sleeve and independent of the driving shaft for locking the blades in normal and reversed positions.

10. In marine propulsion, a driving shaft, a casing carried by the driving shaft and provided with a plurality of radiating arms having bearings formed therein and provided with oppositely disposed longitudinal guiding recesses, one of which communicates with the adjacent bearing, propeller blades having reduced spindles journaled in the bearings, locking lugs extending laterally from the spindles and arranged to register with the guiding recesses, an actuating sleeve, means forming a connection between the spindles of the propeller blades and the actuating sleeve for effecting the reversal of the propeller blades, and locking members slidably mounted in the guiding recesses and actuated by the sleeve to alternately engage the lugs and thereby lock the propeller blades in normal and reversed positions.

11. In marine propulsion, a driving shaft, a casing carried by the driving shaft, a plurality of oscillating propeller blades carried by the casing, an actuating sleeve mounted for rotation with the driving shaft, a head forming a closure for one end of the actuating sleeve, rods forming a pivotal connection between the propeller blades and the sleeve and having their inner ends slidably mounted in said head and provided with

shoulders defining locking recesses, pawls pivotally mounted on the head and adapted to enter the recesses of the rods when the blades are in reversed position, means for positively forcing the pawls within the recesses, means for releasing the locking pawls from the recesses when the sleeve is actuated to return the blades to normal position, and means for locking the propeller blades in normal and reversed positions.

12. In marine propulsion, a driving shaft, a casing carried by the driving shaft and provided with radiating arms having bearings formed therein, detachable face plates secured to the arms at said bearings, propeller blades mounted for oscillation in the bearings and provided with laterally extending locking lugs, there being longitudinally disposed guiding grooves formed in each arm and arranged in register with the locking lugs of the adjacent propeller blade, an actuating sleeve, a connection between the actuating sleeve and each propeller blade for effecting the reversal of the latter, and locking members slidably mounted in the guiding grooves and provided with reduced lips arranged to alternately engage adjacent lugs on the propeller blades for locking the propeller blades in normal and reversed positions.

In testimony whereof I affix my signature in presence of two witnesses.

ISAAC A. HORTMAN. [L. S.]
